Inventor:

UNITED STATES PATENT OFFICE.

FRANK W. WOLFF, OF NEW KENSINGTON, PENNSYLVANIA, ASSIGNOR TO WALTER P. MURPHY, OF NEW YORK, N. Y.

RAILWAY-CAR.

1,393,333.

Specification of Letters Patent. Patented Oct. 11, 1921.

Application filed April 29, 1919. Serial No. 293,405.

To all whom it may concern:

Be it known that I, FRANK W. WOLFF, a citizen of the United States, residing at New Kensington, in the county of Westmoreland 5 and State of Pennsylvania, have invented certain new and useful Improvements in Railway-Cars, of which the following is a specification.

My invention relates to the construction 10 of railway cars, and more particularly to the provision of a reinforcement for the wooden end wall of a railway box car. The end wall of a railway box car is subject to thrusts and pressures of the lading due to inertia and 15 also to racking strains due to the tendency of the car body to weave or swing sidewise and forward and back on the underframe in starting and stopping, rounding curves and passing over inequalities of the track. 20 The cargo thrusts are heaviest ordinarily at the bottom of the end wall because the heavier articles of the lading are usually placed on or near the floor. But the weaving stresses are necessarily most pronounced in 25 the upper part of the box structure. Having these conditions in mind, my invention provides a reinforcing structure for the end wall 30 of a railway car which is calculated to give maximum strength and rigidity to the end 35 of the car by the use of a minimum amount of metal, the invention contemplating both economy of manufacturing cost and also such distribution of the metal of the reinforcement as will minimize weight while meeting the requirements of strength and durability of the structure.

The invention is illustrated, in a preferred embodiment, in the accompanying drawings wherein—

40 Figure 1 is an end elevation of the superstructure of a railway box car reinforced in accordance with my invention.

Fig. 2 is a sectional plan on line 2—2 of Fig. 1.

45 Fig. 3 is a plan view of one end of the car with the roof structure removed.

Fig. 4 is a vertical sectional elevation of the reinforcing structure.

50 Fig. 5 is a diagram of one of the blanks from which the upright members constituting part of the end reinforcement are manufactured, and

Figs. 6, 7 and 8 are views, illustrating the

cross sectional configurations of the reinforcing members at different points along 55 their length, these figures being sectional views on lines 6—6, 7—7 and 8—8 of Fig. 4.

Like characters of reference designate like parts in the several figures of the drawings.

Referring to the drawings, 10 designates 60 the end sheathing of the car, 11 the inner end lining, 12 the corner posts, 13 the end posts, 14 the diagonal braces, 15 the end sill, 16 the end plate and 17 the side plates. The car is provided preferably with two substantially upright reinforcing members 18 65 pressed from rectangular strips or sheets 19 (Fig. 5), the metal being bent along the dotted lines 20, 21, 22 and 23 as shown in this figure. The lower portion of each reinforcing member, the part below the line *a—a*, is in the form of a Z bar of uniform cross 70 sectional configuration. The upper end of the member, the part above the line *b—b*, is in the form of a channel bar, the channel 75 of which is of gradually diminishing depth toward the top and the over all width of which gradually increases toward the top. The intervening portion between the lines *a—a* and *b—b* is of a changing configuration 80 which merges the Z formation into the channel formation. By so forming the upright members they are given very considerable strength at the bottom to resist the cargo thrusts against the lower portion of 85 the end wall of the car. The Z formation which extends preferably about one-third up the end wall, has great strength in the direction longitudinally of the car because of the depth of the outstanding web 24 of the Z, 90 the word "depth" being used in the claims as defining this dimension. The flanges 25 of the reinforcing members are fastened to the car wall in any suitable manner as, for example, by bolts 26 through the end sill, 95 bolts 27 through the end posts, and bolts 28 through the end plate, the upper portions of the reinforcing members, while of less depth than the lower portions, have wider lateral spread so that they are particularly calculated to resist the weaving strains to which 100 the upper part of the superstructure of a box car is subjected. The flanges 29 at the upper ends of the reinforcing members are preferably secured to the end plate by bolts 105 30. These bolts stand at quite a distance

from bolts 28 so as to give the construction strength to withstand lateral stresses. Preferably the lower ends of the reinforcing members have riveted thereto short angles 5 31 which are secured to the end sills by bolts 32.

The upper ends of the reinforcing members are preferably united with a bracing structure, which may be of any suitable 10 character, within the car. This bracing structure is shown as consisting of an angle bar 33 secured to the inside of end plate 16 by bolts 34 and a pair of crossed braces 35 riveted to the angle 33 and to short angle 15 bars 36 which are bolted to the side plates 17 of the car frame, the braces 35 being fastened together at their intersection by a plate 37.

I claim:

20 1. A metal reinforcement for the wooden end wall of a railway car, comprising a pair of substantially upright reinforcing members of maximum depth and minimum width at the bottom and maximum width and 25 minimum depth at the top, and means for anchoring said members to the under frame and roof frame of the car.

20 2. A metal reinforcement for the wooden end wall of a railway car comprising a pair of substantially upright reinforcing members which are of Z formation at the bottom and of channel formation at the top, and means for anchoring said members to the under frame and roof frame of the car.

35 3. A metal reinforcement for the wooden end wall of a railway car comprising a pair of substantially upright reinforcing members which are of Z formation at the bottom and of channel formation at the top and are 40 of maximum depth and minimum width at the bottom and maximum width and minimum depth at the top, and means for anchoring said members to the under frame and roof frame of the car.

45 4. A metal reinforcement for the wooden end wall of a railway car comprising a pair of substantially upright pressed steel members relatively narrow but deep for about one-third of the distance from the floor of 50 the car to the roof, and of diminished depth and increasing width from this level to the roof.

55 5. A metal reinforcement for the wooden end wall of a railway car comprising a pair of substantially upright pressed steel members of Z formation for about one-third of the distance from the floor of the car to the roof and of channel formation at their upper ends.

60 6. A metal reinforcement for the wooden end wall of a railway car comprising a pair of substantially upright pressed steel members of Z formation for about one-third of the distance from the floor of the car to the 65 roof and of channel formation at their upper ends.

ends, the channel portion being of gradually diminishing depth and increasing width toward the top of the car.

7. A metal reinforcement for the wooden end wall of a railway car comprising a pair of substantially upright pressed steel members of Z formation for about one-third of the distance from the floor of the car to the roof and of channel formation at their upper ends, the channel portion being of gradually 70 diminishing depth and increasing width toward the top of the car, and the Z portions of uniform section.

8. A metal reinforcement for the wooden end wall of a railway car comprising a pair of substantially upright pressed steel members, the lower portions of which are of Z formation, the upper portions of which are channel formations and the intervening portions shaped to produce a merging of the 80 Z formation into the channel formation.

9. A metal reinforcement for the wooden end wall of a railway car comprising a pair of substantially upright pressed steel members, the lower portions of which are of Z 90 formation and uniform cross section, the upper portions of which are channel formations and the intervening portions shaped to produce a merging of the Z formation into the channel formation.

95 10. A metal reinforcement for the wooden end wall of a railway car comprising a pair of substantially upright pressed steel members, the lower portions of which are of Z formation and substantially uniform cross 100 section, the upper portions of which are channel formations of diminishing depth and increasing width toward the top and the intervening portions shaped to produce a merging of the Z formation into the channel 105 formation.

11. A pressed steel member composed of a rectangular sheet of metal one end of which member has a Z formation of uniform cross section for some distance and the other end a channel formation of diminishing depth and increasing width in the direction away from the Z formation.

115 12. A pressed steel member composed of a rectangular sheet of metal one end of which member has a Z formation of uniform cross section for some distance and the other end a channel formation of diminishing depth and increasing width in the direction away from the Z formation, and an intervening portion at which the Z formation merges into the channel formation.

120 13. An integral pressed steel member, the cross sectional area of the metal of which is uniform from end to end and which has an end portion of uniform Z shape in cross section, an end portion which is in the form of a flanged channel of gradually decreasing width and increasing depth toward the Z configuration, and an intervening portion 125 130

of constantly changing cross section whereby the Z configuration is merged into the channel configuration.

14. A metal reinforcement for the wooden end wall of a railway car comprising a pair of substantially upright steel members, the lower portions of which are of Z formation,

the upper portions of which are in the form of channels having outstanding lateral flanges, and the intervening portion shaped 10 so as to produce a merging of the Z formation into the channel formation.

FRANK W. WOLFF.
